Horan Ohanian, INVENTOR
BY Victor J. Evans
and Co. ATTORNEY

UNITED STATES PATENT OFFICE

HORAN OHANIAN, OF WATERVLIET, NEW YORK

SIGN

Application filed June 24, 1931. Serial No. 546,604.

This invention relates to signs especially adaptable for displaying advertisements on motor trucks and like vehicles and has for the primary object, the provision of a device of the above stated character which may be easily and quickly installed and removed from the vehicle when desired and when applied may be illuminated so that the advertisement may be observed from a considerable distance and which also will be attractive or ornamental to a casual observer.

Another object of this invention is the provision of a novel mounting for the sign to the vehicle which permits convenient application and removal of the latter from the vehicle and also is designed to cooperate with the illuminating means of the sign so that an electric circuit will be completed between an electrical source and said illuminating means when the sign is installed on the vehicle.

A further object of this invention is the provision of a sign of the above stated character which will be simple, durable and efficient and which may be manufactured and sold at a comparatively low cost.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a front elevation illustrating a sign constructed in accordance with my invention.

Figure 2 is a rear elevation illustrating the same.

Figure 3 is a transverse sectional view taken on the line 3-3 of Figure 1.

Figure 4 is a detail sectional view illustrating a means for mounting one of the illuminating lamps in the sign.

Figure 5 is a perspective view illustrating a supporting hook.

Figure 6 is a similar view illustrating another supporting hook or bracket.

Referring in detail to the drawings, the numeral 1 indicates a casing including a rear

wall 2 and side walls 3 provided with marginal flanges 4 forming a seat for a semi-transparent panel 5 on which characters forming advertisements may be coated or otherwise applied. A frame 6 overlies the edges of the panel 5 and has abutting engagement with flanges 7 formed integral with the marginal flanges 4 of the casing and which are disposed at right angles thereto with the edges of the panel spaced slightly therefrom so that a suitable packing strip 8 may be positioned over the edges of the panel to establish a leak-proof connection between the casing, frame and panel.

Integral ears 9 are formed on the frame 6 and are apertured to receive fasteners 10 which also extend through apertured flanges 11 formed on the ends of substantially U-shaped brackets 12. The arm portions of the brackets 12 snugly fit oppositely disposed sides of the casing 1 and have the bight portions spaced from the rear wall 2 as clearly shown in Figure 3.

The rear wall 2 of the casing 1 is provided with pairs of openings over which are secured electric lamp sockets 13 receiving electric lamps 14 disposed within the casing and have their terminals in abutting engagement with clips 15 connected together by conductors 16 and one of said conductors is connected to a contact plate 17 mounted upon one of the brackets 12. The brackets 12 adjacent their upper ends are provided with slots 18 to receive hook shaped elements 19 secured to a wall or portion 20 of a motor vehicle. One of the hooks 19 has an electrical conductor 21 attached thereto and which forms a portion of an electric circuit from an electrical source while the other conductor 22 of said circuit is grounded to the casing 1 as shown in Figure 2. The hook shaped element 19 which has the conductor 21 connected thereto abuts the contact plate 17 when the device is placed upon the vehicle thus completing an electric circuit to the electric lamps 14 for the purpose of illuminating the advertisement on the panel 5. The hook 19 which has the conductor 21 connected thereto is insulated from the respective bracket 12 and the contact plate 17 is also insulated from

said bracket. The electric lamps are arranged in pairs and one pair is arranged laterally of the other pair as shown in Figure 2 for the purpose of permitting the lamps to more evenly illuminate the panel throughout its width and length.

Brackets 23 are provided with attaching portions 24 bolted or otherwise secured to the portion 20 of the vehicle and each is provided with a spring arm 25 provided with a curved portion 26 adapted to engage under the lugs 9 and flanges 11 cooperating with the hook-shaped elements 19 in firmly attaching the sign to the vehicle and which will permit the sign to be easily removed from the vehicle when desired.

From the foregoing description taken in connection with the accompanying drawings, it will be noted that a very efficient sign has been provided whereby the advertisement carried thereby may be effectively illuminated and which may be easily and conveniently applied and removed from the vehicle and when applied, completes an electric circuit between the lamps and electrical source.

While I have shown and described the preferred embodiment of my invention, it will be understood that minor changes in construction, combination and arrangement of parts may be made without departing from the spirit and scope of my invention, as claimed.

Having thus described my invention, what I claim is:

A sign comprising a casing, a character bearing panel carried by said casing, illuminating lamps in said casing, brackets for said casing and having slots, hook shaped elements engaging in said slots and secured to a vehicle and one of said elements connected to an electrical circuit, electrical means connecting the lamps, a contact plate carried by one of the brackets and electrically connected to one of said lamps and adapted to engage the hook shaped element connected in the electrical circuit, said electrical circuit connected to the casing to provide an electrical return from the circuit, and means secured to the vehicle and engaging the casing for cooperating with the hook shaped elements in securing the casing to the vehicle.

In testimony whereof I affix my signature.

HORAN OHANIAN.
